(57) **CLAIM**

The ornamental design for a golf cart laser yardage holder, as shown.

DESCRIPTION

FIG. 1 is a three dimensional perspective view of the design of the invention showing a phantom outline of a laser yardage meter in the formed fitting in the top of the holder; FIG. 2 is a front side elevational view of the holder of FIG. 1;

FIG. 3 is a rear elevational view of the holder of FIG. 1; FIG. 4 is a left side elevational view of the holder of FIG. 1;

FIG. 5 is a right side elevational view of the holder of FIG. 1;

FIG. 6 is a top plan view of the holder of FIG. 1; and,

FIG. 7 is a bottom plan view of the holder of FIG. 1.

The broken line showing of a golf cart laser yardage measurer is included for the purpose of illustrating non-claimed subject matter and forms no part of the claimed design.
